ROTATION MECHANISM FOR ROCK DRILLS

Application filed May 25, 1929. Serial No. 366,036.

This invention relates to rock drills, but more particularly to a rotation mechanism for fluid actuated rock drills of the hammer type.

5 The objects of the invention are to constantly change the position of the working implement on the work for each blow of the hammer piston, to maintain the weight and the length of the rock drill to a minimum 10 and to rigidly support the rotation mechanism.

Other objects will be in part obvious and in part pointed out hereinafter.

In the drawings illustrating the invention 15 and in which similar reference characters refer to similar parts,

Figure 1 is a longitudinal sectional elevation of a rock drill equipped with rotation mechanism constructed in accordance with 20 the practice of the invention,

Figures 2 and 3 are transverse views taken through Figure 1 on the lines 2—2 and 3—3 looking in the direction indicated by the arrows, and

25 Figure 4 is a perspective view of the rotation bar.

Referring more particularly to the drawings, the invention is shown embodied in a rock drill designated by A and comprising 30 a cylinder B and front and back heads C and D respectively. The cylinder B has a piston chamber E in which is disposed a reciprocating hammer piston F for delivering blows of impact to a working implement G extending 35 into the front head C. In the construction shown a chuck H is housed in the front head C wherein it is adapted to rotate and a chuck bushing J is inserted in the chuck H to interlockingly engage the working implement G.

The chuck H may also extend into the front end of the cylinder A and carries a fluted chuck nut K which is in slidable engagement with flutes L of an extension O carried by 45 the piston F. A bushing P which forms a closure for the front end of the piston chamber E is provided with an extension Q which acts as a bearing for the rearward end of the chuck H.

50 In the rearward end of the cylinder B is

an enlarged cylindrical bore R in the bottom of which is disposed a back cylinder washer S to form a closure for the rearward end of the piston chamber E. In addition to the function described the back cylinder washer 55 also acts as a seat for rotation mechanism which, according to the invention, is located directly rearwardly of the piston chamber E and comprises a rotation bar T extending through the front cylinder washer S and is 60 provided with a plurality of flutes U to interlockingly engage ribs V of a nut W threaded in the rearward end of the piston F.

The rotation bar T carries an integral 65 flange X located in the bore and which seats upon the cylinder washer S and acts as a support for shafts Y upon which are mounted pinions Z to mesh with an internal gear b also in the bore R and supported by the back cylinder washer S. The shafts Y are preferably 70 secured fixedly to the flange X.

The pinions Z are adapted for free rotation on the shafts and are held against endwise movement in one direction by the flange X. A plate c seated on the rearward end of the 75 internal gear b serves to prevent endwise movement of the pinions Z in the opposite direction.

Disposed in the rearward end of the bore R and rearwardly of the rotation mechanism is 80 a motor designated generally by d and comprising a cylinder e and a rotor f rotatable in a chamber g in the cylinder e. The chamber g is shown as being of oblong shape while the rotor f is of cylindrical form and of a diameter equal to the small diameter of the chamber g. The rotor f is disposed centrally of the chamber g thus forming expansion chambers h in the opposite ends of the chamber g.

In the construction shown the rotor f arranged coaxially with the piston chamber E and is keyed to a drive shaft j which extends with one end through the plate c and carries on this end a gear k which meshes with the 95 pinions Z. The opposite end of the drive shaft j extends into the back head D and is provided with a frictionless bearing o seated in an aperture p in the back head. Similarly a frictionless bearing q is seated in the 100

plate *c* to form a bearing for the drive shaft *j* adjacent the gear *k*. The back head *D* is seated directly upon the cylinder *e* and thus forms a closure for both the rearward end 5 of the cylinder *B* and the motor chamber *g*. The plate *c* serves in a similar capacity for the front end of the chamber *g*.

The motor *d* is of the multi-vane type and the rotor *f* is accordingly provided with a 10 plurality of radial slots *r*, four in this instance, and in the slots *r* are slidable vanes *s* which are constantly held with their outermost edges against the wall of the chamber *g* by pressure fluid admitted into the bottom 15 toms of the slots through passages *t* in the rotor *f*. The pressure fluid utilized for this purpose is admitted directly into the slots *r* from the chambers *h*.

In the construction shown the cylinder *e* 20 also serves as a valve chest and accordingly has a valve chamber *u* of annular shape into which open the supply passages *v* formed in this instance in the cylinder *e* and leading from a supply reservoir *w* in the rearward 25 end of the cylinder *e*. In the valve chamber *u* is an annular plate valve *x* of the oscillatory type to control the admission of pressure fluid to the ends of the cylinder. Such pressure fluid is conveyed to the rearward end of the 30 piston chamber *E* through an inlet passage *y* extending through the plate *c*, the internal gear *b* and the back cylinder washer *S*, and pressure fluid is conveyed to the front end of the piston chamber *E* through an inlet passage *z* 35 extending through the plate *c* and the cylinder *B*. Intermediate the ends of the piston chamber *E* are a pair of exhaust ports 2 which are controlled by the piston *F*.

The admission of pressure fluid into the 40 drill is controlled by a throttle valve *3* disposed in the back head *D* and having a central chamber *4* which may be in constant communication with a source of pressure fluid supply through suitable connections (not 45 shown). In the wall of the throttle valve *3* is a port *5* to register with a passage *6* leading to the supply reservoir *w*.

The throttle valve *3* is preferably also used as a means for controlling the admission of 50 pressure fluid to the chamber *g*, and when so used may be provided with a port *7* which in the open position of the throttle valve *3* is adapted to register with a passage *8* in the back head *D* and leading to a groove *9* in the 55 rearward end of the cylinder *e*.

From the groove *9* lead passages *10* to the expansion chambers *h* for conveying pressure fluid thereto to act against the vanes *s* for rotating the rotor *f*.

60 The exhaust of fluid from the expansion chambers *h* is effected through exhaust passages *11* opening in this instance into an exhaust chamber *12* formed in the periphery of the cylinder *e* to act as a muffler for the fluid 65 issuing from the expansion chambers, and in

the wall of the cylinder *B* are exhaust ports 13 to convey the fluid from the exhaust chamber *12* to the atmosphere.

The drill *A* may be provided with the usual means for supplying cleansing fluid to the 70 drill steel for removing the cuttings from the drill hole. The means shown for this purpose comprises a water tube *14* which extends from the back head through the drill and into the working implement *G*. Inasmuch that 75 the various elements used for transmitting the rotary motion of the rotor to the chuck are disposed coaxially of the cylinder *B* the water tube *14* may be disposed through these elements and is therefore supported by these elements at points along its length to protect it against the whipping action to which it would be otherwise subjected due to the vibration set up in the drill during its operation. Any well known means, such as a plug, 80 15 may be used for securing the water tube *14* fixedly in the back head *D*.

The operation of the device is as follows: When it is desired to set the piston *F* and the rotor *f* in motion the throttle valve *3* may 90 be rotated to the open position. Pressure fluid will then flow through the passage *6* into the supply reservoir *w* and from thence through the supply passages *v* into the valve chamber *u* where it will be distributed to the 95 ends of the piston chamber *E* by the valve *x*.

In the open position of the throttle valve pressure fluid will also flow through the passage *8*, the groove *9* and the passages *10* into the expansion chambers *h* to act against the 100 vanes *s* for rotating the rotor *f*. Upon the admission of pressure fluid into the expansion chambers a portion thereof will flow through the passages *t* into the slots *r* to act against the 105 ends of the vanes *s* for pressing the outer ends of the vanes firmly against the walls of the chamber *g* to prevent leakage of pressure fluid from one side of the vanes to the other.

As illustrated the rotor *f* is adapted to rotate in a counter-clockwise direction and as 110 the vanes *s* overrun the exhaust passages *11* the pressure fluid will be exhausted through these passages into the exhaust chamber *12* and from thence to the atmosphere through the exhaust ports *13*. In this way the rotor, 115 and thus also the associated train of elements connecting it with the chuck *H* will be constantly rotated during the operation of the drill and the position of the working implement will therefore be continually changed, 120 for each blow of the hammer piston *F*.

I claim:

1. In a rock drill, the combination of a cylinder and a chuck, a piston in the cylinder slidably interlocked with the chuck, a rotary motor in the rear end of the cylinder coaxial with the piston and comprising a rotor, a gear connected to rotate with the rotor and disposed between the motor and the cylinder, a bar slidably interlocked with the pis- 125 130

ton, and a pinion carried by the bar and meshing with the gear to rotate the bar for transmitting rotary movement from the motor to the chuck.

5 2. In a rock drill, the combination of a cylinder and a chuck, a piston in the cylinder slidably interlocked with the chuck, a rotary motor in the rearward end of the cylinder coaxial with the piston and the chuck
10 and comprising a rotor, a gear connected to rotate with the rotor and disposed between the motor and the cylinder, a bar extending coaxially into the cylinder and carrying a flange, an internal gear encircling the gear,
15 and pinions carried by the flange and meshing with the gears to transmit the rotary movement of the rotor to the chuck.

3. In a rock drill, the combination of a hammer cylinder and a chuck, a piston in the cylinder slidably interlocked with the chuck, a motor cylinder in the hammer cylinder, a rotor in the motor cylinder, a bar interlockingly engaging the piston, means for transmitting the rotary movement of the rotor to
25 the bar, a valve chamber in the motor cylinder, inlet passages leading from the valve chamber to the cylinder, a valve in the valve chamber to control the inlet passages, and means for controlling the admission of pressure fluid to the motor cylinder and the valve chamber.

4. In a rock drill, the combination of a hammer cylinder and a chuck, a motor in the cylinder comprising a motor cylinder and a
35 rotor, a transmission extending coaxially through the hammer cylinder to transmit the rotary movement of the rotor to the chuck, a valve chamber in the motor cylinder, inlet passages leading from the valve chamber to
40 the hammer cylinder, a valve in the valve chamber controlling the inlet passages, and means for controlling the admission of pressure fluid to the motor cylinder and the valve chamber.

45 5. In a rock drill, the combination of a hammer cylinder and a chuck, a piston in the cylinder slidably interlocked with the chuck, a motor cylinder in the hammer cylinder having a groove forming an exhaust chamber, a
50 rotor in the motor cylinder, means extending coaxially into the hammer cylinder and interlockingly engaging the piston, means for transmitting the rotary movement of the rotor to the first said means, means for admitting pressure fluid to the cylinders, exhaust
55 passages in the motor cylinder opening into the exhaust chamber, and exhaust ports in the hammer cylinder affording communication between the exhaust chamber and the atmosphere.

In testimony whereof I have signed this specification.

WILLIAM A. SMITH, Jr.
